CANDLE HOLDER

Walter I. Bieger, Minneapolis, Minn., assignor to Arthur Salm Inc., Chicago, Ill., a corporation of Illinois

Filed May 21, 1963, Ser. No. 74,992

Term of patent 14 years

(Cl. D48—2)

Fig. 1

Fig. 2

Fig. 3

Fig. 4

FIG. 1 is a top plan view of a candle holder showing my new design wherein the base has a wood grain pattern;

FIG. 2 is a perspective view thereof on a reduced scale;

FIG. 3 is a front view thereof; and

FIG. 4 is a side elevation of a modified form of the holder shown in FIG. 1 wherein the base is plain view thereof.

The showing of three candles in broken lines in FIG. 2 is for illustrative purposes only.

I claim:

The ornamental design for a candle holder, substantially as shown and described.
